UNITED STATES PATENT OFFICE.

EDWARD BADLAM AND DAVID E. SOUTHWICK, OF OGDENSBURG, N. Y.

VEHICLE-WHEEL.

SPECIFICATION forming part of Letters Patent No. 269,373, dated December 19, 1882.

Application filed February 6, 1882. (No model.)

To all whom it may concern:

Be it known that we, EDWARD BADLAM and DAVID E. SOUTHWICK, of Ogdensburg, in the county of St. Lawrence and State of New York, 5 have invented certain new and useful Improvements in Wheels for Vehicles; and we do hereby declare that the following is a full, clear, and exact description of the invention, which will enable others skilled in the art to which it appertains to make and use the same, reference being had to the accompanying drawings, which form a part of this specification, and in which—

Figure 1 is a longitudinal section of the hub of a vehicle-wheel of our improved construction. Fig. 2 is a cross-section of the hub through line xx in Fig. 1. Fig. 3 is a sectional view of one of the spokes, with its socket for attaching it to the felly. Fig. 4 is a detail view of the rubber-cushioned spring-ferrule which forms the core of the hub; and Figs. 5, 6, and 7 are sectional views of the spoke-tenons, illustrating modifications in the construction and shape of the same.

Similar letters of reference indicate corresponding parts in all the figures.

Our invention contemplates an improved construction of vehicle-wheels, and has for its object to combine durability of construction with 30 a certain degree of elasticity, so as to provide a smooth-running wheel, which may be easily taken apart, when desired, for the purpose of repair, and as easily put together.

To this end our improvement consists in the 35 construction and combination of parts, herein-after more fully described and claimed.

In the accompanying drawings, A represents the axle-arm, which, if not made of steel or iron, should have the usual thimble-skein.

B is the axle-box, which is screw-threaded 40 on the outside, the threads running in different directions on opposite sides of the hub-body. In other words, it has a right-handed screw-thread on one side of this and a left-hand thread on the other side.

The hub is composed of five concentric parts or sections—viz., an outer sleeve, C, which is cast or made in one piece with the nut-sleeve c' , and has a swelled rim or annular shoulder, C', 50 on its inner side, a corresponding sleeve, D, which has, likewise, a swelled rim or annular shoulder or flange, D', and is made in one piece

with the said box D², and a central part or body composed of three disks, F, G, and H, which are clamped between the parts C C' and D D', as clearly shown in Fig. 1 of the drawings. Box B, with its several parts of the hub, is held upon the axle by a flanged nut, E, as usual. The middle part of the hub or hub-body, which receives the spokes, is, as above stated, composed of three disks, F, G, and H, each of which has a central circular bore or aperture. The disks are concentric, and their several central apertures register with one another. The two outer disks, F and H, have 65 semicircular radial recesses f h , while the central or middle disk, G, has a double series of similar radial recesses—one series on opposite sides or faces, as shown respectively at g and g' in Fig. 1, those on one side alternating with those on the other side. The hub-disks F, G, and H are so placed upon or against one another that the radial recesses f of disk F will register with the radial recesses g on the contiguous side or face of disk G, while, again, the 70 radial recesses g' on the opposite side of the latter will register with the radial recesses h of disk H. Thus two rows of alternating bores are formed—viz., f g and g' h —radiating from the center of the hub and extending from its 75 circumference to the central aperture. Into the latter is inserted a sleeve or ferrule, J, made of steel or other suitable spring metal, which is split longitudinally on one side, as shown at j , and is provided with an interior rubber packing, K. Leather, felt, or other suitable material 80 may be used instead of rubber for the ring or packing-sleeve K, if desired. The axle-box B is inserted through the packing-sleeve K, and rotates with it and the hub.

I are the spokes, the inner tenoned ends, i , of which are screw-threaded, and are screwed into the radial bores or recesses f g and g' h , which are likewise screw-threaded to receive them. The spokes are screwed in far enough 95 to cause their inner ends to impinge upon the spring sleeve or ferrule, J, as shown in Fig. 2. In Fig. 3 we have shown the outer end of one of the spokes, with its clamp or socket, felly, and tire. The spoke I is reduced, as shown at i' , to form a tenon which will fit tightly into the socket L, which is made with flaring wings l l , and a tapering thimble, l' , between said wings.

M is the felly, which is shaped to fit between

the wings or socket-clamps *l l*, and *N* is the tire, which has a countersunk hole, *n*, for each spoke.

m is a long screw, which may be either tapering or of even size throughout its length. This screw or screw-bolt is inserted through a hole bored through the felly and tire, through the tapering thimble *l'*, and up into the spoke, as clearly shown in the drawings.

10 The spokes may be made of steel, iron, or wood, as desired, and if made of metal they may be either solid or hollow. In Figs. 5, 6, and 7 we have shown cross-sections of the tenoned ends *v* of the spokes, the two first-named figures representing sections through tubular steel spokes, and Fig. 7 a cross-section through a wooden spoke. The sleeve or ferrule *J* being split or slitted on one side permits it to give or yield to inward pressure of the spokes, and 15 of their disks *F*, *G*, and *H*, the inside elastic core forming a cushion around the middle part of the axle-box. Thus we provide for an elastic and smooth-running wheel, the tire of which may be tightened by screwing the spokes 20 up in their respective threaded sockets.

It is obvious that two hub-disks may be used instead of three, in which case of course the radial spoke-recesses of one register with those of the other.

Having thus described our invention, we 30 claim and desire to secure by Letters Patent of the United States—

In a wheel for vehicles, the combination of the axle-box *B*, hub-sleeves *C C'* and *D D'*, elastic or yielding hub-core *J K*, and two or 35 more concentric hub-disks, *F G H*, having radial semi-cylindrical or tapering recesses on their contiguous faces registering with one another, said disks being clamped between sleeves *C C'* and *D D'*, substantially as and 40 for the purpose herein shown and described.

In testimony that we claim the foregoing as our own we have hereto affixed our signatures in presence of two witnesses.

EDWARD BADLAM.
DAVID E. SOUTHWICK.
